UNITED STATES PATENT OFFICE

167,043

DRAFTSMAN'S TEMPLATE

Glenn W. Kintz, Anchorage, Territory of Alaska

Application March 26, 1952, Serial No. 19,056

Term of patent 14 years

(Cl. D52—1)

To all whom it may concern:

Be it known that I, Glenn W. Kintz, a citizen of the United States of America, residing at Anchorage, Alaska, have invented a new, original, and ornamental Design for a Draftsman's Template, of which the following is a specification, reference being had to the accompanying drawing, forming a part thereof wherein:

I claim:

The ornamental design for a draftsman's template, as shown.

GLENN W. KINTZ.
